UNITED STATES PATENT OFFICE.

ALBERT GOTTSCHALK, OF NEW YORK, N. Y., ASSIGNOR TO NATIONAL PNEUMATIC COMPANY, OF CHICAGO, ILLINOIS, A CORPORATION OF WEST VIRGINIA.

DOOR-OPERATING APPARATUS.

1,111,959.

Specification of Letters Patent. Patented Sept. 29, 1914.

Application filed February 15, 1912. Serial No. 677,763.

To all whom it may concern:

Be it known that I, ALBERT GOTTSCHALK, a citizen of the United States, residing at New York, in the county of New York and State of New York, have invented new and useful Improvements in Door-Operating Apparatus, of which the following is a specification.

This invention relates to fluid pressure apparatus for operating doors and the like, and more particularly to car doors for sub-way, elevated railway, or electric traction service generally, and is in the nature of an improvement in the apparatus covered in my prior applications, Ser. No. 519,432, filed September 24, 1909, Ser. No. 593,032, filed Nov. 18, 1910, and Ser. No. 639,611, filed July 20, 1911. As set forth in said prior applications, when the piston of the actuating motor reaches the end of its stroke in the closing movement of the door it is adapted to uncover a port for admitting fluid to the valve shifting cylinder to cause the movement of the valve to cut off or lap position, but where, as is usual in this class of devices, a cup-leather packing is employed on the actuating piston, it might happen that fluid would be admitted to the valve shifting cylinder, and the valve be closed, slightly before the door reached the completely closed position. One of the objects of my present improvement is to provide means for overcoming this difficulty, and to positively effect the opening of this port only when the piston reaches the extreme end of its movement. This is particularly important in connection with a door operating device having a latch mechanism for locking the device in the closed position of the door, for if the door is not quite closed, the latch mechanism will not be locked, and the door is then liable to be thrown open accidentally when the car or train is running.

According to the improvement set forth in the last application above noted, when the door is arrested in its closing movement by striking a person or other obstruction in its path, the pressure which accumulates upon the piston in the cylinder opens a spring seated valve and passes to a valve device which temporarily cuts off and then automatically opens the supply of fluid pressure to the cylinder, so that the door may be pushed back and the person or obstruction

be released, and that the door will then automatically close without special attention on the part of the operator. While this apparatus may be entirely sufficient for ordinary purposes, it may be desirable in some instances that the door be positively moved back toward open position, when a person or other obstruction is encountered, and another object of my present invention is to provide improved means for this purpose.

Another object is to provide improved means for cushioning the door to prevent slamming even when the pressure accidentally builds up to an excessive degree upon the piston.

In the accompanying drawings: Figure 1 is a plan, with certain parts shown in horizontal section, of a preferred form of my improvement; Fig. 2, a side elevation of the same, one end of the valve shifting cylinder being indicated in section; Fig. 3, a plan of a portion of the cylinder shown upon a larger scale; Fig. 4, a longitudinal vertical section of the portion of the cylinder and valve device shown in Fig. 3; and Fig. 5, a section of a pressure retaining valve which may be attached to the outlet port from one end of the cylinder.

As shown and described in my prior applications above referred to, my improved door operating apparatus comprises in general, a cylinder, 8, containing two opposite pistons, 9, with an intermediate rod or bar, 10, having rack teeth for engaging the segmental gear, 12, mounted on the shaft, 13, for rocking the arm, 14, to actuate the door when fluid under pressure is admitted from a supply pipe or port, 20, to either end of the cylinder through the respective ports, 24 and 25. A rotary valve, adapted to be operated by lever, 19, through any suitable connections, serves to control communication from the supply port to the ports, 24 and 25, and from these ports to the atmosphere, through the exhaust ports, 29^a and 29^b. For the purpose of automatically cutting off the supply of fluid to the cylinder when the piston has reached the end of its stroke in either opening or closing the door, a valve shifting cylinder, 30, is provided, containing opposite pistons, 33, and intermediate rack bar, 34, engaging the segmental gear mounted on sleeve, 35, having a projection, 36, for engaging the lever, 19, and shifting the valve to intermediate or lap position, when

fluid is admitted to either end of the valve shifting cylinder, as fully set forth in my prior applications.

Where the rocker arm, 14, for actuating the door, occupies an inclined position when the door is closed, a latch, 53, operated by a spring, 54, and a releasing piston, 51, in a cylinder, 50, may be employed, all as fully described in my prior application Ser. No. 10 639,611, above mentioned, and under these conditions, it is important that the mechanism should move sufficiently far, in the closing movement of the door, to permit the latch lever to lock the same in the closed 15 position. Otherwise there would be danger of the door being accidentally thrown open when the car is running.

When a leather packed piston is employed, and a port at the end of the stroke is 20 adapted to be uncovered thereby to admit fluid to the valve shifting cylinder, as in said prior application, if the fluid should leak past the leather before the piston quite reaches the end of its stroke, the valve may 25 be shifted before the door is completely closed and latched, but according to one of the features of my present improvement, the complete closing of the door is insured by providing a normally closed valve, 32^b, controlling the ports or passages, 32 and 32^a, 30 from the main cylinder, 8, to the valve shifting cylinder, 30, and having a stem or plunger, 32^a, adapted to be positively engaged by the metal face of the piston, 9, at the 35 extreme end of its movement to open said valve, thereby admitting the fluid to the valve shifting cylinder to lap the valve, when, but not before, the door has reached its closed or latched position.

40 In my prior application Ser. No. 639,611, I have described a device operating, when the door is arrested by encountering an obstruction during its closing movement, automatically to temporarily cut off the supply of fluid to the cylinder, exhaust the same to the atmosphere, and then to again turn on the supply, this device comprising a valve, 40, and piston head, 41, subject to the pressure in cylinder, 8, through port, 39, and 45 normally held seated by spring, 42, but adapted, when the pressure in the cylinder is sufficient to overcome said spring, to open communication through port or passage, 60, to the cylinder, 61, containing a piston, 62, 50 for operating the valves, 63 and 64, for controlling the admission of fluid through passages, 70, 67, and 72, into the cylinder, 8, and the exhaust therefrom through ports, 72 and 65. When the door is obstructed and 55 fluid is admitted from the main cylinder to act on piston, 62, the latter closes valve, 63, to cut off the supply of fluid and opens valve, 64, thereby exhausting the main cylinder to the atmosphere and consequently releasing the pressure from cylinder, 61, so

that the spring 68, immediately depresses piston, 62, closing the exhaust valve, 64, and again opening the supply of fluid to the cylinder through valve, 63, this operation being repeated until the obstruction is removed 70 and the door moves to its closed position without any special attention on the part of the operator.

According to my present improvement, I provide, in addition to the device above described, means for automatically admitting fluid to reverse the movement of the door when the same is arrested by an obstruction in its closing movement and the supply of fluid to the closing end of the cylinder is 80 cut off. As shown in the drawings, a preferred form of this feature of my improvement may comprise a valve, 78, normally held closed by a spring, 79, and the pressure of fluid from a source of supply through a 85 pipe or passage, 82, but adapted to be opened momentarily by means of a piston, 77, in cylinder, 75, and thereby admit fluid through check valve, 80, and passage, 81, into the opening end of the main cylinder for causing a reverse movement of the main piston, 9, and the door. The pressure operated valve, 40, and head, 41, may also serve to control the supply of fluid to cylinder, 75, in any convenient manner, as by means of a 95 passage or pipe, 76, communicating with the passage, 60, so that the two pistons, 62 and 77, may be actuated at substantially the same time. Any slow leakage of pressure at valve, 78, will escape around the stem of 100 the piston, 77, to the atmosphere through port, 83.

It will now be seen that, when the door is obstructed in its closing movement, and the valve, 40, opens to supply fluid to the 105 piston, 62, to operate valves, 63 and 64, to cut off the supply to the cylinder through passages, 25, 70, 67, and 72, and open an exhaust therefrom to the atmosphere, the piston, 77, is also operated to open the valve, 110 78, and supply fluid to the opposite end of the cylinder, 8, to reverse the movement of the piston, and move the door away from the obstruction. As the pressure remains on the piston, 77, only temporarily, the valve, 78, 115 is opened momentarily and then closed, but a sufficient amount of fluid under pressure is admitted to the cylinder, 8, to cause a reverse movement of the piston, 9, even though this end of the main cylinder is at 120 the time open to an exhaust through a restricted discharge port, 29^a, at the rotary valve which has been turned to its closing position by the lever, 19.

The check valve, 80, prevents escape of 125 fluid to the atmosphere through leakage discharge port, 83, when said fluid is admitted through the rotary valve and port, 24, to that end of the main cylinder in the normal operation of opening the door. 130

After a reverse movement of the mechanism, as above described, the supply of fluid to the closing end of the cylinder is again automatically opened and the operation may 5 be repeated several times or until the obstruction is removed from the path of the door.

If desired, a pressure retaining valve device, such as indicated at 90, having a valve, 10 91, and an adjustable spring, 92, (see Fig. 5,) may be connected to the exhaust port, 29^a, for the purpose of retaining a certain minimum degree of pressure in the left end of the main cylinder when the rotary valve 15 is in its closing position and fluid is being admitted through port, 25, to the right end of the cylinder for closing the door. During this movement, the opposite piston head, 9, compresses the air in that end of the cylinder 20 until the pressure acting through the discharge port, 29^a, upon the valve, 91, is sufficient to overcome the spring, 92. The compressed air will then escape to the atmosphere, and the piston will be subject to 25 the cushion of this amount of back pressure as determined by the spring of the retaining valve. This back pressure upon the piston 30 9, may even be sufficient to cause a reverse movement of the piston and door when the same is obstructed in its closing movement, and the supply is cut off, without the use of valve, 78, but when both of these devices are employed, the action is naturally much more positive, since the air cannot escape from 35 the left end of the cylinder through the discharge port, 29^a, until a certain degree of pressure has accumulated therein. The retaining valve also prevents slamming of the door, in case a high pressure should, for any 40 reason, be built up in the right end of the cylinder before the piston has cleared the port, 39. When the rotary valve is turned to the position for opening the door, the air compressed by the movement of the piston 45 in the right end of the cylinder is discharged to the atmosphere through restricted port, 29^b, as described in said prior application.

Where the retaining valve is employed, the discharge port, 29^b, does not need to be restricted as in the former case, since the back pressure is sufficient to cushion the movement of the mechanism. In the normal intermediate position of the valve, other exhaust openings may be provided for both 50 ends of the cylinder, and, if desired, discharge ports for the exhaust of fluid from the main cylinder may be located in the valve shifting cylinder at the end of the stroke of its piston, as before described in 55 said prior applications.

From the foregoing description, it will now be apparent that the retaining valve 60 may be employed either with or without the valve device for automatically supplying fluid to the opening end of the motor when

the door is obstructed, and that the latter device may also be used without the retaining valve, if desired.

While, for convenience, I have shown the valve devices for cutting off the supply to 70 the closing end of the motor, and for admitting fluid to the opposite end, when the door is obstructed, as separately mounted upon opposite ends of the main cylinder, it is obvious that they may be combined or 75 arranged in any other suitable manner, as desired.

Having now described my invention, what I claim as new, and desire to secure by Letters Patent is:—

1. In a door operating apparatus, the combination with a fluid pressure motor, and connecting means for actuating the door, of fluid pressure actuated means operating automatically upon the arrest of the door during 80 its closing movement, for admitting fluid to the opposite end of the motor to cause a reverse movement of the door.

2. In a door operating apparatus, the combination with a fluid pressure motor and 90 connecting means for actuating the door, of a valve for controlling the supply of fluid to the motor, and additional valve means operating automatically upon the arrest of the door during its closing movement, for 95 supplying fluid to the opposite end of the motor to cause a reverse movement of the door.

3. In a door operating apparatus, the combination with a fluid pressure motor and 100 connecting means for actuating the door, of a manually operated valve device for controlling the supply of fluid to the motor for opening and closing the door, and additional valve means operating automatically upon 105 the arrest of the door during its closing movement, for cutting off the supply of fluid to the closing side of said motor and supplying fluid to the opposite side thereof to cause a reverse movement of the door.

4. In a door operating apparatus, the combination with a fluid pressure motor and connecting means for actuating the door, of a valve device operated by the pressure in 110 said motor, when the door is arrested during its closing movement, to supply fluid to the opposite end of the motor to reverse the movement thereof.

5. In a door operating apparatus, the combination with a fluid pressure motor and 115 connecting means for actuating the door, of a valve device operated by the pressure in said motor, when the door is arrested during its closing movement, to cut off the supply of fluid to the closing end of the motor 120 and open a supply of fluid to the opposite end to cause a reverse movement of the motor.

6. In a door operating apparatus, the combination with a fluid pressure motor, 125

and connecting means for actuating the door, of a valve device operated by a predetermined degree of pressure in the closing end of the motor to temporarily cut off the supply to said end and momentarily supply fluid to the opposite end of the motor.

7. In a door operating apparatus, the combination with a fluid pressure motor, and connecting means for actuating the door, of valve device operating automatically upon the arrest of the door during its closing movement, to temporarily cut off the supply of fluid to said end and momentarily open and then cut off a supply of fluid to the opposite end of the motor.

8. In a door operating apparatus, the combination of a cylinder having an outlet port, a piston adapted to open said port, connecting mechanism actuated by the piston for moving the door, a valve actuated by the movement of the piston at the end of its stroke to open communication through said outlet port, and means operated by the discharge through said outlet for cutting off the supply of fluid to the cylinder.

9. In a door operating apparatus, the combination of a cylinder having an outlet port, a piston adapted to open said port, connecting mechanism actuated by the piston for moving the door, a valve actuated by the movement of the piston at the end of its stroke to open communication through said outlet port, a valve device for control-

ling the supply of fluid to the cylinder, a latch for locking the mechanism in its closed position, and means operated by the discharge through said outlet for cutting off the supply of fluid to the cylinder.

10. In a door operating apparatus, the combination with a fluid pressure motor, and connecting mechanism for actuating the door, of a latch for locking the mechanism in the closed position of the door, a valve for controlling the supply of fluid to the motor, a fluid pressure device for closing said valve, and a valve operated by the movement of the motor at the extreme end of its stroke for supplying fluid to said device.

11. In a door operating apparatus, the combination with a cylinder, piston and connecting mechanism for actuating the door, of a valve for controlling the supply of fluid to one end of the cylinder for closing the door, a communication from the opposite end to a discharge port, a pressure retaining valve connected to said discharge port, and means for freely exhausting said cylinder at the end of the stroke of the piston.

In testimony whereof I have hereunto set my hand.

ALBERT GOTTSCHALK.
